UNITED STATES PATENT OFFICE.

KENNETH A. CANTIN, OF HONOLULU, TERRITORY OF HAWAII.

PORABLE FLASH-LIGHT.

1,313,516.

Specification of Letters Patent.

Patented Aug. 19, 1919.

Application filed March 28, 1918. Serial No. 225,270.

To all whom it may concern:

Be it known that I, KENNETH A. CANTIN, a citizen of the United States, residing at Honolulu, in the Territory of Hawaii, have 5 invented certain new and useful Improvements in Portable Flash-Lights; and I do hereby declare the following to be a full, clear, and exact description of the invention, such as will enable others skilled in 10 the art to which it appertains to make and use the same.

The present invention relates to new and useful improvements in portable flashlights of that general type including a lamp carrying casing in which a battery is removably 15 housed.

It is primarily the object of this invention to embody a variable resistance in the lamp circuit of a flashlight, whereby the 20 intensity of said light may be varied at will.

It is more particularly an object to incorporate a rheostat element in flashlights of the conventional nature, in a most economical manner, and without adding materially to the size or general proportion of 25 the flashlight.

With the above and other objects and advantages in view, the invention resides more particularly in the novel combination, formation and arrangement of parts herein-after specifically described and pointed out in the appended claims.

In the accompanying drawing:—

Figure 1 is an elevational view of a flashlight embodying the present invention,

Fig. 2 is a vertical longitudinal sectional view therethrough,

Fig. 3 is a transverse sectional view therethrough on the line 3—3 of Fig. 2,

Fig. 4 is a diagrammatic view of the lamp circuit.

Referring now more particularly to the accompanying drawings, there is provided a main tubular casing 5 which has a removable cap 6 at one end for retaining the usual battery 7 in the casing, and which is open at its other end. A sheet of insulating material 12 is wrapped about the open end portion of the main casing, and wound upon 45 this sheet is a coil 13 forming the rheostat. Wrapped about said coil is a second sheet of insulating material 14, and disposed about and inclosing the second sheet of material to present a finished appearance to 50 the structure is a tubular casing 15 which has one end extended past the open end of

the main casing and carrying a cupped reflector 8 insulated therefrom and provided with a socket receiving the usual lamp 10. A bull's eye is disposed at the mouth of the 60 reflector. One side of this casing 15 is struck outwardly longitudinally of the axis thereof to form an elongated trough shaped projection 16. Slidable in a longitudinal slot 17 in this projection is a spring finger 18, 65 which carries outwardly of the wall of the projection a button 19, and which, at its inner end, is slidably engageable with selective convolutions of the wire 12 through a longitudinal slot 20 formed in the insulating sheet 14. One end of the rheostat coil 12 connects, as shown more particularly in Fig. 4, with the lamp receiving socket. The other end of the rheostat has no electrical contact, and the main casing 5 is connected 70 with the battery contact by a metallic strip 21 extending from the trough 16 longitudinally along the inner periphery of the casing 5 for contact with the cap 6, it being observed that the button 19 and spring pin 80 18 form the usual means for effecting a connection between the main casing and the battery contact 21. In the present structure, the slidable mounting for the push button is merely elongated so that the button may 85 slide over the coils of the rheostat. Thus a rheostat element is embodied in the flashlight without affecting the size or proportion of the general structure thereof.

Tracing the lamp circuit, the current 90 passes from the usual end pole 22 of the battery through the lamp by the usual direct contact. From the lamp socket the current passes through the rheostat coil 12, and from thence through the spring finger 18 to the 95 main casing, from whence it passes through the connection 21 back into the battery. Thus when the spring finger is pushed to one end of the slot 17, and out of contact with any of the rheostat coils, the circuit is 100 broken.

What is claimed, is,

1. In a portable flash light including a battery receiving casing and a lamp carried thereby, a resistance member wound about 105 the casing and insulated therefrom, an outer casing surrounding the rheostat member and insulated therefrom, a contact member slidably carried by said outer casing for selective engagement with the convolutions of 110 the rheostat member and an electrical connection between the casings.

2. In a portable flash light including a battery receiving casing and a lamp carried thereby, a sheet of insulation wrapped about the casing, a resistance member coiled about said insulation, a second sheet of insulation wrapped about the resistance member and provided with a longitudinal slot, an outer casing disposed about the second sheet of insulation, a contact member slidably carried by said outer casing and engageable with the resistance member through said slot, and an electrical connection between the casings.
3. In a portable flash light including a battery receiving casing and a lamp carried thereby, a sheet of insulation wrapped about the casing, a resistance member coiled about

said insulation, a second sheet of insulation wrapped about the resistance member and provided with a longitudinal slot, an outer casing disposed about the second sheet of insulation, and struck outwardly along one side to form a trough like slotted projection, a button slideable on said projection, and a spring finger on the button extending through the slot of the projection and engageable with the resistance member. 20 25

In testimony whereof, I affix my signature, in the presence of two witnesses.

KENNETH A. CANTIN.
